UNITED STATES PATENT OFFICE.

SAXTON S. BARRETT, OF CHICAGO, ILLINOIS; THE NORTHERN TRUST COMPANY, EXECUTOR OF SAID SAXTON S. BARRETT, DECEASED, ASSIGNOR TO MARY K. BARRETT, OF GLENCOE, ILLINOIS.

TEMPORARY BINDER.

1,109,027.

Specification of Letters Patent.

Patented Sept. 1, 1914.

Application filed May 10, 1912. Serial No. 696,361.

To all whom it may concern:

Be it known that I, SAXTON S. BARRETT, a citizen of the United States, residing at Chicago, in the county of Cook and State 5 of Illinois, have invented certain new and useful Improvements in Temporary Binders, of which the following is a specification, reference being had to the accompanying drawings.

10 My invention relates to temporary binders for magazines, newspapers and other periodicals, and has for its objects to provide an improved binder which will be substantial but cheap in construction and which 15 may readily be made of sufficient capacity to accommodate a number of magazines; also to provide retaining devices of new and improved construction which will securely hold the periodicals in place and will not 20 readily become detached accidentally. I accomplish these objects as illustrated in the drawings and as hereinafter described.

What I regard as new is set forth in the claims.

25 In the accompanying drawings,—Figure 1 is a perspective view of my improved binder, a part of one of the covers being broken away; Fig. 2 is a longitudinal vertical section on line 2—2 of Fig. 3, also partly 30 broken away; Fig. 3 is an end view; Fig. 4 is a perspective view of one end portion of one of the retaining-strips or rods; Fig. 5 is a perspective view of one of the locking-plates by which the free end of the retaining 35 device is secured; Fig. 6 is an elevation thereof showing the retaining-strip partly inserted; Fig. 7 is a perspective view of a locking-plate having a number of slots; and Figs. 8 and 9 are perspective views of a 40 modified form of locking plate, each slot having a plurality of engaging devices.

Referring to the drawings,—10 indicates the back-piece of the binder, which, in the form illustrated, is a substantially flat, steel 45 plate of suitable dimensions, but this may be varied as desired.

11—12 indicate the covers, which are secured at the side margins of the back-piece 10 by external and internal canvas strips 50 13—14 in the usual way.

15 indicates an end-plate formed by bending up one end of the back-piece 10. Said plate is provided with one or more slots 16 to receive the ends of binding strips or rods

17, as shown in Fig. 1, said slots being large 55 enough to permit the strips 17 to move freely through them and to be swung up and down, as required. As best shown in Fig. 4, each binding strip 17 is provided with a pin 18 located outside the end-plate 15, thereby permitting endwise movement of the retaining-strip but preventing it from being withdrawn from the slot 16 in which it is placed.

In Fig. 2 I have shown the binder equipped with an improved form of retaining-strip composed of a thin strip of metal having rounded or elliptical ferrules 17^a which are spaced apart thereon, and serve to prevent the strip from cutting through the binding of the periodical, without destroying its flexibility. In Fig. 2 two ferrules are shown, secured at 28 near the ends of the strip 17. 19 indicates an end-plate formed at the opposite end of the back 10 by bending up a portion thereof, as shown 70 in Fig. 1, said end-plate having suitable slots to receive the free ends of the retaining-strip 17. Such slots are provided with suitable engaging devices to engage the retaining-strips and hold them in place. 80

In Figs. 1, 2 and 3, I have illustrated a construction in which slots 20 are provided which extend, generally, diagonally downward from the upper margin of the end-plate 19, notches 21 being provided above 85 said slots to receive the retaining-strips and hold them in place after insertion. In practice, the retaining-strips are twisted axially until they may be moved down through the slots 20 and when released are automatically 90 restored by their own elasticity to a vertical position and enter the notches 21. As the magazine held by any strip exerts outward pressure upon it, the strips are thus held properly in position. For more conveniently 95 operating the retaining-strips 17, I provide them with finger-pieces 22, as shown in Figs. 1, 2 and 3.

While the construction of locking-plate 19, shown in Figs. 1, 2 and 3, is satisfactory 100 for many purposes, I prefer to employ locking plates having the construction shown in Figs. 5 to 9, in which the liability of accidental disengagement of the retaining-strips is much less. As shown in Fig. 6, 105 such locking plates are provided with one or more slots 23 each of which is entered by an angular passage 24. As clearly illus-

trated in said figure, the upper portion of said passage is vertical, or substantially so, and the lower portion is inclined, forming an angle 25 intermediate the length of the 5 entering passage. Opposite such angle is a downwardly-projecting lug 26 which forms one side of the entering passage 24 and of a notch 27 which receives the retaining-strip in its locking position. The purpose of providing the angular passage described is to 10 deflect or bend the retaining-strip between its upper and lower margins, as illustrated in Fig. 6, when it is moved through said passage, as well as to require its being twisted 15 axially, thus presenting considerable resistance to the movement of the retaining-strip through said passage. Consequently, if the retaining-strip should drop down out of the notch 27 it could not be withdrawn from the 20 slot 23 without considerable pressure being applied to it. The retaining-strips are made of steel or other suitable material capable of being deflected sufficiently to pass through the passage 24, without, however, 25 being permanently deflected or bent, and the strip is held against axial rotation at its hinge and so as to secure the twisting action described. Locking plates having this form of locking devices may be employed either 30 as an integral part of the back of the binder, as shown in Figs. 1, 2 and 3, or they may be formed separately and attached to binder backs of different forms. In Fig. 8 I have 35 shown the same type of locking device applied to a locking-plate having two retaining lugs 26^a—26^b, the construction being otherwise the same. In Fig. 7 I have shown a locking-plate having a plurality of slots similar to the slot 23. Preferably, where 40 the locking-plate is provided with a large number of slots 23 the entering passages 24 of the slots at one end portion of the plate are engaged oppositely to those at the other end portion, as shown in Fig. 7. In Fig. 9 45 I have illustrated locking plates having a plurality of slots 23 each provided with a plurality of lugs 26^a—26^b. The purpose of providing the plurality of lugs shown in Figs. 8 and 9 is to permit the retaining-strip 50 to be adjusted to suit magazines of different styles of binding.

My improved retaining-strip, and the securing devices therefor, may be employed in connection with other suitable forms of supporting back pieces if desired, as, for example, in the newspaper binder described in my application of even date herewith, Serial No. 696,364.

That which I claim as my invention, and 60 desire to secure by Letters Patent, is,—

1. A locking-plate for binders having a slot adapted to receive and secure a retaining-strip, said slot having means for bend-

ing or deflecting the retaining-strip between its upper and lower margins as it passes 65 therethrough.

2. A locking-plate for binders having a slot adapted to receive and secure a retaining-strip, said slot having an angular entering 70 passage for bending or deflecting the retaining-strip between its upper and lower margins as it passes therethrough.

3. A binder, comprising a suitable back having a locking-plate connected therewith, and a retaining-strip, said retaining-strip 75 being capable of being temporarily bent or deflected between its upper and lower margins, said locking-plate having a slot to receive said strip, said slot having means for so deflecting said retaining-strip as it enters 80 the slot.

4. A binder, comprising a suitable back having a locking-plate connected therewith, and a retaining-strip, said retaining-strip being capable of being temporarily bent or 85 deflected between its upper and lower margins, said locking-plate having a slot to receive said strip, said slot having an angular entering passage for so deflecting said retaining-strip as it enters the slot. 90

5. A locking-plate for binders having a slot adapted to receive and secure a retaining-strip, said slot having means for bending or deflecting the retaining-strip between its upper and lower margins and for twisting 95 said strip axially as it passes therethrough.

6. A locking-plate for binders having a slot adapted to receive and secure a retaining-strip, said slot having an angular entering passage for bending or deflecting the retaining-strip between its upper and lower margins as it passes therethrough, a portion 100 of said slot being inclined for twisting said strip axially. 105

7. A binder, comprising a back-piece, one or more retaining-strips capable of being temporarily bent or deflected between their upper and lower margins and of being twisted axially, means connecting one end 110 portion of said strips with the back-piece and holding the same against axial rotation, and a securing device for the other end of said strip or strips having means for bending said strip or strips between their upper and lower margins and for twisting them axially. 115

8. A retaining-strip for binders, comprising a flexible strip angular in cross-section, having a ferrule thereon adapted to prevent 120 the strip from injuring papers held by the strip.
